The ornamental design for a saw blade hub, as shown and described.

DESCRIPTION

FIG. 1 is a front elevation view of a saw blade hub showing our new design, the rear elevation view being identical; FIG. 2 is a top plan view, the bottom plan view being identical;

FIG. 3 is a side elevation view thereof, the opposite side being unornamented;

FIG. 4 is a front elevation view of a saw blade hub showing our new design, the rear elevation view being identical;

FIG. 5 is a top plan view, the bottom plan view being identical; and,

FIG. 6 is a side elevation view thereof, the opposite side being unornamented.

The broken line showings in FIGS. 1, 2, 4 and 5 are illustrative only and form no part of the claimed design.
